UNITED STATES PATENT OFFICE

MAE C. KAPUSTKA, OF CHICAGO, ILLINOIS

END-CURL FASTENER

Application filed April 20, 1929. Serial No. 356,682.

My invention relates to hair clasps or fasteners, the primary object being to provide an improved form of fastener or clasp that may be advantageously used to secure the end curls particularly produced in water waving.

When end curls have heretofore been produced they have been secured by the use of some form of hair pin, and I am aware ¹⁰ also that hair clasps have heretofore been devised, but in so far as I am aware such clasps are not adapted for the proper securement and fastening of the end curls as produced by water waving.

¹⁵ My improved device is cheap to manufacture, is quickly and easily applied and detached from the hair, and is very efficient in holding end curls in position until the hair is thoroughly dry and the curl receives its ²⁰ ultimate dry form.

Other objects of my invention will appear from the following description, which is directed to the preferred embodiment thereof as hereinafter described and illustrated ²⁵ in the accompanying drawing which forms a part of the specification, the novel features being more specifically set forth in the appended claims.

In the said drawings:

³⁰ Fig. 1 is a top plan view of my improved end curl fastener.

Fig. 2 is a plan view of one of the two part members of the device that have an elastic hinge-like connection whereby to ³⁵ clamp the curl, the section being taken approximately on the line 2—2 of Fig. 3, looking downwardly in the direction indicated by the arrows. In this view the section line would follow the telescoping offset portions ⁴⁰ of the two plates constituting the co-operating jaws of the device.

Fig. 3 is a sectional view on line 3—3 of Fig. 1.

Fig. 4 is a view graphically illustrating ⁴⁵ the manner of application of the device to the end curl of a wisp of hair.

Fig. 5 is a sectional view similar to the view shown in Fig. 3 illustrating a modification of one of the jaws of the device for the ⁵⁰ purpose of providing a lock or snap for se-

curing the parts of the device in closed position upon a curl of hair.

The preferred form of the invention constructed in accordance with that illustrated in Figs. 1 to 3 inclusive is made of some ⁵⁵ suitable grade of sheet metal having sufficient resiliency or elasticity to insure the retention of the two parts of the clasp or fastener together when in closed position upon a curl or ringlet of hair. The invention is ⁶⁰ directed particularly to a form of device that may be readily stamped from sheet metal, economy in manufacture being one of the essentials of a device of this character in connection with which, as in the use of ⁶⁵ ordinary hair pins and the like, there is of necessity considerable wastage due to losses during application and subsequent use of the same.

I prefer to make the device of an integral ⁷⁰ sheet of metal, the same being made of two parts or leaves joined by an integral connecting portion, the latter being designated by the reference character 15, the two co-operating parts of the device, which I term ⁷⁵ for convenience, the upper and lower plates of the clasp, being designated generally by the reference characters 16 and 17, respectively. In the form of the device shown in Figs. 1 and 2 I depend solely upon the ⁸⁰ spring quality or elasticity of the material to cause the plates 16 and 17 of the fastener to clamp upon the hair, when in position. My curl fastener being particularly adapted for the securement of end curls is generally ⁸⁵ made quite small, since such curls in themselves possess a relatively small body, being generally not larger than an ordinary ten cent piece. These devices embodying my invention may therefore be made in different sizes when used for the securement of different size end curls, the ordinary size being for an end curl of approximately the size of a ten cent piece.

The top and bottom plates 16 and 17 will ⁹⁵ be provided with telescoping offset portions, the bottom portion 17 having the offset part 19 and the upper plate 16 having the telescoping offset portion 20.

In applying the fastener to a ringlet or ¹⁰⁰

end curl, such ringlet or curl will be clamped between the telescoping depressed portions 19 and 20, the hair to be held therein for a considerable space of time until the ringlets or curls are thoroughly dried therein. These fasteners are generally used when the hair is damp or wet, and I prefer that the device be constructed so as to permit readily the escape of water in the form of steam or moisture. This I accomplish by perforating the upper plate 16 both in the bottom of the depressed portion 20 as at 25, and in the peripheral portion of the top plate 16 also, as designated at 26. These 15 perforations 25 and 26 serve the double purpose of permitting the escape of moisture in hair clamped in the device for drying and they also serve as centering means for projections 27 in the lower plate 19. I provide 20 also similar projections 28 in the peripheral portion of the lower plate to co-operate with the perforations 26 in the upper plate. The projections 27 act to pierce the ringlet or end curl of hair when clamped in 25 position and to hold the same firmly in the retainer. These serve to assist in centering the plates with reference to each other and also in the same manner as the corresponding perforations and projections 25 and 27, 30 respectively, assist in holding any ringlets or curls of hair that may project toward the peripheral portions of the device when not in use.

An important feature of my invention resides in the construction of the top and bottom plates 16 and 17 at the ends thereof adjacent from the connecting or spring hinge portion 15. The plates 16 have lateral end portions 30 and 31 that are wider than the corresponding lateral end portions 32 and 33 of the lower plate, while the lower plate is longer than the upper plate, projecting beyond the same a sufficient distance, as illustrated at 36, Figs. 1 and 3 to enable an operator to grasp the projecting side portions 30 and 31 of the upper plate between two fingers and permitting the separation of the two plates against the spring connection by grasping the projecting portion of the lower plate 36 with another finger of that hand or another hand.

In Fig. 5 I show a slight modification of the preferred form of the invention in which a locking device is provided by means of the integral spring tongue 40, which is shown at the end of the plate 17, the same having an overhanging angular portion 41 adapted to co-operate with the forward lip of the upper plate 16 to clamp or lock the two plates firmly together in their assembled position upon a ringlet or curl of hair in the event that the spring or resiliency of the spring hinge part 15 is not sufficient for this purpose.

65. The device may be readily and quickly

clamped upon ringlets of hair and retain the same in position indefinitely or as long as desired, and the perforated condition of the upper plate makes it possible for the hair to dry readily either with the assistance of 70 drying apparatus or in the atmosphere.

While I have preferred to make the size of the telescoping portions of the device as approximately that of a dime for use on ordinary ringlets or end curls, I do not desire 75 to be limited as to size, for it will be apparent that the device may be constructed of sizes much larger than that herein illustrated and described, and may be used advantageously for the securement and fixation of all sizes and textures of hair, and obviously, the size of the device will depend upon the size of the curl to be produced.

It will be obvious that those skilled in the art may modify my device without departing from the purpose and spirit of the invention.

What I claim as my invention and desire to secure by Letters Patent is:

1. An end curl fastener comprising two 90 separable clamping members provided with co-operating substantially circular telescoping portions, said telescoping portions being adapted to receive an end curl therebetween, and means for holding said members in 95 clamping position upon a ringlet or curl of hair.

2. An end curl fastener comprising separable clamping members formed from an integral sheet of elastic material, the said 100 separable clamping members being connected by an elastic yoke and being provided with substantially centrally located telescoping offset portions, said offset portions being adapted to receive an end curl therebetween. 105

3. An end curl fastener comprising separable clamping members formed from an integral sheet of elastic material, the said 110 separable clamping members being connected by an elastic yoke and being provided with substantially centrally located telescoping offset portions, said offset portions being 115 adapted to receive an end curl therebetween, and means for locking said members in clamping position upon a ringlet or curl of hair.

4. As an article of manufacture, an end curl fastener comprising two separable clamping members of substantially circular form, each being provided with offset centrally located portions telescoping with each other, said telescoping portions being 120 adapted to receive an end curl therebetween.

5. As an article of manufacture, an end curl fastener comprising two separable clamping members of substantially circular form, each being provided with offset centrally located portions telescoping with each other, said telescoping portions being 125 adapted to receive an end curl therebetween, 130

and means for holding said members in clamping position upon a ringlet or curl of hair.

6. As an article of manufacture, an end curl fastener formed from a sheet of flexible material and comprising two substantially co-terminus body portions connected by an integral flexible elastic neck, the terminal portion of one of said body members being wider than the corresponding terminal portion of the other body member, there being a projecting part of the other body member beyond the extremity of the said wider terminal portion whereby the wider terminal portion may be grasped between two fingers of one hand of an operator while pressure is applied by a finger on the other hand of the operator to separate the body portions of the said device in adjusting a ringlet or curl of hair therein.

7. As an article of manufacture, an end curl fastener adapted to be stamped from an integral sheet of flexible elastic material and comprising two separable body portions flexibly and elastically connected together, each of said body portions being provided with offset surfaces adapted to have telescopic relation with respect to each other when the device is in clamping position upon a curl or ringlet of hair, there being openings in one of the said separable body portions adjacent the said telescoping offset portions whereby to permit the drying of a curl or ringlet of hair when clamped in the device.

8. As an article of manufacture, an end curl fastener comprising two integrally connected body portions provided with offset telescoping portions adapted to receive an end curl or ringlet of hair therebetween, perforations in one of said body portions for permitting the drying of a curl or ringlet of hair in position in the device, and co-operating recesses and projections within the said telescoping offset portions whereby to secure a curl or ringlet of hair in operative position therein.

9. As an article of manufacture, an end curl fastener formed of flexible elastic sheet metal comprising two separable body portions provided with co-operating telescoping offset portions adapted to receive therein a curl or ringlet of hair, and a plurality of co-operating recesses and projections on the said body portion of the device whereby to assist in holding a curl or ringlet of hair when in position between said body portions of the device.

10. As an article of manufacture, an end curl fastener comprising two separable clamping members adapted to grip an end curl between them with an elastic pressure exerted upon the curl, there being perforations in one of said body portions for permitting the drying of a curl or ringlet of

hair in position between the body portions of the device, and co-operating projections formed on the surface of the other of the said body portions of the device and being adapted to co-operate with and project into the said perforations in the other said body portion.

11. As an article of manufacture, an end curl fastener comprising two separable clamping members adapted to grip an end curl between them, and means for detachably securing said separable clamping members together to exert pressure upon a curl of hair therebetween, there being an offset portion in one of said clamping members to provide a chamber for receiving a curl or ringlet of hair in position between said members, perforations in one of said clamping members for permitting the drying of a curl or ringlet of hair held in position between said members, and projections on the other of said members adapted to extend into said perforations.

In testimony whereof I have signed my name to this specification.

MAE C. KAPUSTKA.
